CASING FOR RECEIPT PRINTER FOR A GASOLINE DISPENSER

Robert B. Gaylor, Jr., Pittsburgh, Pa., assignor to Symington Wayne Corporation, Salisbury, Md., a corporation of Maryland

Filed July 28, 1966, Ser. No. 3,234

Term of patent 14 years

(Cl. D52—2)

Fig. 1.

Fig. 2.

Fig. 3.

Fig. 6.

Fig. 5.

Fig. 4.

Fig. 7.

FIG. 1 is a front perspective view of a casing for receipt printer for a gasoline dispenser showing my new design;

FIG. 2 is an enlarged front perspective view thereof;

FIG. 3 is another enlarged front perspective view thereof, showing the casing in an open position;

FIG. 4 is a further enlarged front elevational view thereof;

FIG. 5 is a side elevational view of FIG. 4;

FIG. 6 is a top plan view of FIG. 4; and

FIG. 7 is a bottom plan view of FIG. 4.

The broken line showing of a gasoline dispenser in FIGS. 1 and 5 and a receipt printer in FIG. 3 is for purposes of illustration only.

We claim:

The ornamental design for a casing for receipt printer for a gasoline dispenser, as shown and described.
